UNITED STATES PATENT OFFICE

2,040,582

VERTICAL RETORT FOR THE CARBONIZATION OF COAL AND THE LIKE

Frederick Joseph West and Ernest West, Miles Platting, Manchester, England, assignors to West's Gas Improvement Company Limited, Miles Platting, Manchester, England, a company of Great Britain

Application December 6, 1933, Serial No. 701,198
In Great Britain December 8, 1932

2 Claims. (Cl. 202—220)

This invention relates to vertical retorts for the carbonization of coal and the like, and has for its object to provide an improved construction of retort, with its heating means, which will effect considerable economy in heat requisite to effect the carbonization operation and which will by reason of its simplicity and method of heating and operation be readily started up and controlled.

10 The invention comprises a vertical retort for the carbonization of coal and the like in which the carbonization space is of ring-like or annular form, the inner wall forming the outer wall of vertical combustion chambers bounded by the 15 carbonization space, so that the coal during carbonization forms an enclosure for the combustion chambers and absorbs the heat thereof until carbonization is completed, when a new charge is introduced to the carbonization space. With 20 our improvement there is no portion of the combustion chambers (except the waste gas outlet) not bounded by the carbonization zone so that direct radiation from the combustion chambers to the atmosphere is prevented. We are thus 25 enabled to effect considerable economy in heat consumption without the necessity for specially lagging or insulating the setting.

The invention further comprises the arrangement 30 of the combustion chambers in sectional plan in the form of the spaces between the spokes of a wheel of which the rim is the carbonization space and the hub serves to keep the combustion gases close against the wall of the carbonization chamber.

35 The invention further comprises the arrangement at the base of the annular carbonization space of an annular cooling space divided into two superposed sections with removable means for separating the two sections, the lower section having a discharge door thereon, and means admitting steam to the two sections.

Referring to the accompanying explanatory drawings:—

Figure 1 is a sectional elevation of one form of 45 retort constructed in accordance with this invention.

Figure 2 is a sectional plan view on the line 2—2 of Figure 1.

Figure 3 is a sectional plan view on the line 50 3—3 of Figure 1.

Figure 4 is a front elevation of the retort setting, with the passages for supplying air and gas to the base of the setting shown in section.

Figure 5 is a detail view partly in sectional elevation and partly in elevation showing the means

for lowering and raising the coke discharge door at the base of the annular retort.

Figure 6 is a sectional plan view on the line 6—6 of Figure 5.

Figure 7 is partly a sectional elevation and 5 partly an elevation of a modified construction of retort setting in accordance with this invention.

Figure 8 is a sectional plan view on the line 8—8 of Figure 7.

Figure 9 is a sectional plan view on the line 9—9 of Figure 7.

Figure 10 is a sectional plan view drawn to an enlarged scale of part of the means shown in Figure 7 for controlling the descent of the coke 15 to the lower section of the coke cooling space.

Figure 11 is an enlarged view of the part of 20 said means shown in Figure 7.

In Figures 1—6, the retort setting comprises an 25 annular carbonization space *a* and a series of combustion chambers *b*, the outer wall *c* of the combustion chambers being the inner wall of the carbonization space. The outer wall *d* of the latter space is enclosed within brickwork *e* and an outer metal casing *f* which gives strength 30 and rigidity to the setting. There are suitable inspection doors through the metal case, brickwork *e* and retort wall *d*, one of which is shown at *g* in Figures 1 and 4.

The annular carbonization chamber *a* diverges 35 from top to bottom and is provided at its top with gas offtakes, one of which is shown at *h*, in Figure 4, and with feeding hoppers *i*, Figure 1, which receive coal from a central hopper *j* and coke from an outer hopper *k*. Valve plates *m* control the passage of coal or coke to the hoppers *i* and so to the annular carbonization space. After the latter has been emptied breeze is fed into the said space to cover the discharge door *n* at the base of the retort. Afterwards, the 40 coal to be carbonized is fed into the carbonization space *a*.

The secondary air for combustion is supplied under pressure by the pipe *o*, Figure 1, which passes through a heater *p*, heated by the waste 45 gases from the combustion chambers *b*, down a lagged pipe *q* to an annular passage *r* in the base of the setting, which communicates with a series of vertical gas passages *r*¹, one for each combustion chamber. The waste gas flue from the tops 50 of the combustion chambers *b* to the secondary air heater *p* is shown at *s*. The vertical passages *r*¹ communicate with each of the combustion chambers *b* by passages *t*, each of which is controlled by a damper plate *u*.

The producer gas for the combustion chambers enters the central passage *v* in the base of the setting and issues through individual ducts *w* leading one to each combustion chamber, the exit being adjacent to a secondary air duct or orifice so that a flame is produced by the combustion of the producer gas, which travels up the combustion chamber and heats the carbonization space. Each duct *w* is controlled by a 10 damper *w*¹.

The coke discharge door *n* which is of annular or ring-like form is supported by two rams *x* at diametrically opposite points, the said rams having rack teeth thereon engaged by pinions *y* 15 upon shafts *z* which are rotated by worms and worm wheels *20* from the shaft *21* having the hand wheel *22* thereon.

The upper surface of the door *n* slopes outwards to direct the coke being discharged from 20 the annular retort space outwardly for convenience of collection.

The coke in the retort space is steamed before discharge for the production of water gas in the known manner.

25 With our improvement, the carbonization space which is of annular form is in direct contact with the combustion chambers within so that all the heating space is enclosed by the carbonization space. The external wall of the carbonization space can be strengthened by the enclosure thereof within the metal casing *f*. The said external wall is not externally heated so that heat loss by radiation from outer combustion chambers is obviated. The coal itself acts 30 as a heat insulator whilst carbonization proceeds. When carbonization is completed, the charge will fall freely through the carbonization space for discharge past the door *n*.

In the construction of retort settings shown 40 in Figures 7-11, we interpose a cooling and steaming space between the discharge door *n* and the base of the carbonization space *a* which surrounds the combustion chambers *b*. The said cooling space which is a continuation downwards of the 45 carbonization space comprises two sections *A* and *B*, Figure 7, the capacity of the two sections together being such that they will not quite accommodate all the coke from the remainder of the annular space, but the capacity of the part 50 *B* is equal or approximately to that of *A*. Between *A* and *B* is located the means, shown in detail in Figures 10 and 11, for holding up the coke in *A* whilst the coke in *B* is being discharged past the door *n*. Such means consist of a number 55 of plates *23* each pivoted at *24* in a fixed annular frame member *25*, there being a peg *26* in each plate which projects into a cam slot *27*, the said cam slots being in a ring *28* having helical rack teeth *29* thereon on its periphery en- 60 gaged by a helix *30* on the spindle *31*. By rotating the latter, the plates *23* are turned from a position in which they act as a door to hold up the coke in the space *B*, which is the position shown in full lines in the figures, to a position 65 in which they are withdrawn from the annular coke space so that coke can fall freely from *B* to *A*. Steam for steaming the coke can be admitted at *32* and *33* or at other desired parts.

Assuming that the whole of the annular space 70 from top to bottom of the retort setting is full of coke because carbonization of the charge in the carbonization zone is completed, then, due to steaming, the coke in the spaces *A* and *B* will be relatively cool. The spindle *31* is turned to 75 cause the plates *23* to hold up the coke in *A* and

the door *n* is lowered to discharge the contents of the space *B*. *n* is then closed and the plates *23* displaced to allow coke to fall from *A* to *B*. The coke from the carbonization space of course falls simultaneously partly into the space *A*. The 5 plates *23* are again moved to hold up the coke in *A* whilst *B* is discharged through the door *n*. When the latter is again closed and the plates *23* displaced outwards, the charge which was previously in the carbonization zone, will now 10 occupy the spaces *A* and *B* and a short distance above *A*. The excess material above what is contained in *A* and *B* serves eventually to cover first the plates *23* and then the door *n* during the discharge stages and as it is cooler than the 15 incandescent newly carbonized material, it acts to protect such plates and door against overheating.

In the construction shown in Figures 1-6, coke breeze is fed into the carbonization space before 20 the coal charge in order to cover and protect the discharge door during the carbonization period.

In the constructions illustrated, the divisions between the combustion chambers strengthen the chambers and act to conduct heat to the 25 carbonization space. The combustion chambers in effect occupy the spaces between what might be termed a wheel shape in sectional plan (see Figures 2 and 8), the spokes of the wheel forming the divisions between the chambers and the hub 30 of the wheel ensuring that the combustion products are maintained close to the inner wall of the carbonization space.

Due to the small amount of brickwork involved in a complete setting, the drying of a 35 setting and the starting of carbonization can be effected in a fraction of the time taken with usual constructions of vertical retorts.

We claim:

1. An intermittently operating vertical retort 40 comprising an unbroken annular carbonization chamber diverging from top to bottom, means adapted to insert material to be carbonized directly into the top of said annular chamber, means to withdraw material from the base of 45 said chamber, means to remove gas from the top of said chamber, and a plurality of vertical combustion chambers located within and bounded by said annular carbonization chamber adapted to heat the contents of said carbonization 50 chamber, together with means for the supply of combustible to the base of said combustion chambers and for withdrawing the products of combustion from the upper ends thereof centrally above the carbonization chamber, said combustion 55 chambers being arranged in the form of a unitary structure, in horizontal cross-section whereof said chambers are arranged in the form of the spaces between the spokes of a wheel having a central hub and whereof the rim is formed 60 by the inner wall of the annular carbonization space aforesaid.

2. An intermittently operating vertical retort comprising an unbroken annular carbonization chamber diverging from top to bottom, means 65 adapted to insert material to be carbonized directly into the top of said annular chamber, means to withdraw material from the base of said chamber, means to remove gas from the top of said chamber, a vertical combustion chamber located centrally within and bounded by said annular carbonization chamber and adapted to form the sole heating means for the contents of 70 said carbonization chamber, the carbonization chamber forming therefore a heat insulating sur- 75

round for the heating chamber, with means for supplying combustible to the base of said combustion chamber and for withdrawing the products of combustion from the upper end thereof above the carbonization chamber, the lower portion of said annular carbonization chamber extending below the combustion chamber, with means to inject steam into said extension, removable means adapted to divide said extension

into two superposed sections, with coke discharge means at the base of the lower section, said removable means being constituted by a series of plates each pivoted for movement in a horizontal plane from a position in which it extends across said annular extension to a position in which it is clear thereof.
